COAL OIL BURNER,
APPLICATION FILED MAY 14, 1917.

Patented Mar. 26, 1918.
2 SHEETS—SHEET 2.

UNITED STATES PATENT OFFICE.

PHILIP H. SPAULDING, OF HINSDALE, ILLINOIS.

COAL-OIL BURNER.

1,260,471.

Specification of Letters Patent. Patented Mar. 26, 1918.

Application filed May 14, 1917. Serial No. 163,511.

To all whom it may concern:

Be it known that I, PHILIP H. SPAULDING, a citizen of the United States of America, residing at Hinsdale, in the county of Du⁵ page and State of Illinois, have invented certain new and useful Improvements in Coal-Oil Burners, of which the following is a specification, reference being had therein to the accompanying drawing.

10 This invention relates to a coal oil burner and has for its principal object the production of a structure which will easily vaporize the oil for causing the gas to readily burn as discharged from the burners, the flame at 15 each burner striking against a spreader so as to further heat the conducting pipes for vaporizing the oil.

Another object of this invention is the production of a coal oil burner wherein a 20 minimum number of parts are employed, thus making the burner cheaper and more durable in construction, although arranging the pipes in such manner as to readily vaporize the oil before the same is conducted 25 to the nipples of the burner.

Another object of this invention is the production of a coal oil burner wherein generating pans are positioned upon the pipes beneath the nipples of the burner for heating the vaporizing pipes, these pans being 30 provided with simple and efficient straps for supporting the same and holding the pans against side displacement.

With these and other objects in view, this 35 invention consists in general of certain novel combinations, constructions and arrangements of parts as will be hereinafter fully described and claimed.

In the drawings:

40 Figure 1 is a top plan view of the coal oil burner as constructed in accordance with this invention.

Fig. 2 is a side elevation of the coal oil burner.

45 Fig. 3 is a vertical section taken on the line 3—3, Fig. 2, looking in the direction of the arrows.

Fig. 4 is a section taken on the line 4—4, Fig. 2, looking in the direction of the 50 arrows.

Fig. 5 is a section taken on the line 5—5, Fig. 1.

Fig. 6 is a section taken on the line 6—6, Fig. 1, looking in the direction of the 55 arrows.

Fig. 7 is a vertical section taken on the

line 7—7, Fig. 2, looking in the direction of the arrows.

Fig. 8 is a section taken on the line 8—8, Fig. 1, looking in the direction of the 60 arrows, and illustrating the manner in which the generating pan is held against displacement.

Fig. 9 is a section taken on the line 9—9, Fig. 1.

Fig. 10 is a section taken on the line 10—10, Fig. 8.

Fig. 11 is a section taken on line 11—11, Fig. 1.

Referring to the accompanying drawings 70 by numerals it will be seen that the valves 1 are connected by the T 2 to a suitable supply 3 leading from a tank or similar source of supply which it is not deemed necessary to disclose. The parallel side pipes 4 have 75 vertical extensions 5 at one end, and these extensions 5 terminate in the horizontal projections 6 which are connected to the valves 1.

In order to hold the side pipes 4 from 80 spreading, elbows 7 are carried upon their free ends and these elbows 7 are connected by a short pipe 8, as shown clearly in Fig. 1. In this manner it will be seen that the side pipes 4 will be positively retained in spaced 85 relation.

Each side pipe comprises a primary section 9 and an auxiliary section 10. These sections are connected together by T-joints 11 and 12. The auxiliary section 10 connected to the T-joint 11 is internally threaded, as indicated at 13 in Fig. 5, so as to receive an externally-threaded plug 14. By this construction it is obvious that oil admitted by one of the valves into the side pipe 95 4 carrying the T-joint 11 will be prevented from passing into the auxiliary section 10 of the side pipe. The primary section 9 of the remaining side pipe is also connected to the T-joint 12 so as to supply this T-joint with 100 oil when oil is admitted by the remaining valve, but in order to prevent the oil from passing into the auxiliary section 10 or through the elbows 7 a plug 14' is threaded into the auxiliary section 10 connected to the 105 T-joint 12 as shown clearly in Fig. 11. By the foregoing description, it will be seen that oil will be prevented from passing beyond the T-joints of the respective side pipes 4.

A one-piece burner pipe is connected to 110 each of the T-joints 11 and 12 and the construction of the burner pipe is clearly shown

in Figs. 3 and 7. The burner pipe comprises a pair of sides 15 connected by the horizontal top 16. One of the sides 15 is threaded into engagement with its respective T-joint 5 while the remaining side is provided with a short horizontal portion 17 terminating in a vertical burner portion 18. This burner portion is externally threaded so as to permit the burner cap 19 to be screwed thereon as 10 is shown at 20. The burner cap 19 is provided with a reduced opening 21 for purposes to be hereinafter set forth.

The spreader 22 is provided with a plurality of spurs 23 upon its periphery as 15 shown clearly in Fig. 1. This spreader 22 is retained upon the horizontal portion 16 of each burner pipe by means of a clamp 24 which fits over the horizontal portion 16 of the burner pipe for permitting the bolts 25 20 to be passed through the feet 26 of the clamp 24 and through the spreader 22 for holding the spreader against accidental displacement. U-shaped supporting bands 27 have their ends coiled to form supporting sleeves 25 28 and 29. These sleeves 28 and 29 fit upon the side pipes 4 whereby the bands will be held in engagement with these side pipes, as shown in Figs. 7 and 8. It will be noted 30 that the sleeves 28 fit upon each end of the T-joints 11 and 12 while the bands converge toward their opposite ends. The generating 35 pans 30 rest upon the bands 27 and fit between the side pipes 4. It will further be seen by referring particularly to Fig. 8 that these generating pans 30 are positioned below the burner cap 19. These pans are held 40 fixedly upon the bands 27 by means of rivets 31 whereby the rivets will hold the bands and generating pans as a single unit. As a consequence, since the sleeves 28 fit upon the 45 ends of the T-joints 11 and 12, it is obvious that the bands and pan will be held against longitudinal movement along the side pipes since the joints will hold the sleeves 28 from 50 sliding in either direction. In this manner, the generating pans will be held at all times in their correct positions beneath the burner caps 19.

When this coal oil burner is in use, it is 50 intended to provide generating pans 30 with any suitable material such for instance, as asbestos meal or mineral wool. When it is desired to ignite either of the burners a quantity of alcohol of a suitable amount is poured 55 into either of the generating pans and is then ignited. After the alcohol has been burned a few minutes, or long enough to heat the burner pipe, the proper valve is actuated for admitting oil into the burner 60 pipe. Owing to the superheated condition of the burner pipe, the oil passing therethrough will be vaporized so as to pass in the form of gas from the cap of the burner pipe, thus permitting the gas to be ignited. 65 Therefore, a comparatively large blue flame

will issue from the burner cap which will strike against the spreader 22 carried thereabove. The flame will then pass around between the spurs 23 formed on the periphery of the spreader so as to produce a large 70 flame of very intense heat. This will continue to heat the burner pipe for continuing the vaporizing of the oil as the oil passes through the burner pipe.

From the foregoing description it will be 75 seen that a very simple and efficient coal oil burner has been produced which is formed of a comparatively few number of parts and which is constructed so as to prevent needless quantities of oil passing through the 80 sections of pipe not in use while the formation of each burner will cause the oil to be quickly vaporized as the oil passes therethrough. It will also be seen that the generating pans are carried upon the supporting straps mounted upon the side pipes so as to hold the generating pans against longitudinal movement along the side pipes owing to the permanent connection of these bands and the generating pan and the manner of 90 having the sleeves of these bands engaging one of the joints of each burner pipe.

What is claimed is:—

1. In a coal oil burner of the class described, the combination with a pair of side 95 pipes, a joint connected to one of said pipes, a burner pipe carried by said joint, U-shaped supporting bands positioned beneath said burner pipe, said bands having rolled ends thereby forming sleeves fitting upon said 100 first-mentioned pipes, a generating pan carried by said bands, said pan being permanently secured to said bands, a plurality of said sleeves engaging the ends of said joint, whereby said bands will be held against 105 movement along said first-mentioned pipes thereby holding said generating pan against accidental displacement.

2. In a coal oil burner of the class described, the combination of a pair of side 110 pipes, means for supplying said side pipes with oil, a joint carried by each of said side pipes, a plug positioned in each of said side pipes adjacent said joints whereby oil will be prevented from passing beyond said 115 joints, burner pipes comprising sides having a horizontal connecting portion, one side of each burner pipe being connected to one of said joints and the remaining side of each burner pipe having a horizontal projection terminating in a vertical projection, a burner cap carried by said vertical projection, said burner cap having an opening, a spreader carried upon the horizontal portion of each burner pipe whereby said spreader will be 120 directly above said cap whereby oil passing through said burner pipe will be generated thereby causing the oil passing from said burner cap to be vaporized and easily ignited so as to direct a flame against said spreader. 130

3. In a coal oil burner of the class described, the combination with a pair of side pipes, of means for supplying said pipes with oil, a burner pipe extending from each side pipe, a generating pan positioned beneath each burner pipe, U-shaped supporting bands having sleeves formed at their ends, said sleeves engaging said first-men-

tioned pipes whereby said bands will be supported for carrying said pans, said pans being permanently mounted upon said bands, and means for holding said bands from moving from a set position upon said side pipes. 10

In testimony whereof I hereunto affix my signature.

PHILIP H. SPAULDING.
